EVERETT L. THOMPSON, OF DOVER, NEW JERSEY, ASSIGNOR TO SYPHO-CHEMICAL SPRINKLER CORPORATION, OF CROTON-ON-HUDSON, NEW YORK, A CORPORATION OF NEW YORK.

AUTOMATIC FIRE-EXTINGUISHING APPARATUS.

1,287,800.

Specification of Letters Patent.

Patented Dec. 17, 1918.

Application filed April 17, 1914. Serial No. 832,518.

To all whom it may concern:

Be it known that I, EVERETT L. THOMPSON, a citizen of the United States, and resident of Dover, Morris county, State of New Jersey, have made a certain new and useful Invention Relating to Automatic Fire-Extinguishing Apparatus, of which the following is a specification, taken in connection with the accompanying drawing, which forms part of the same.

This invention relates especially to automatic fire extinguishing apparatus in which the distributing system may comprise automatic sprinkler heads, hose connections or other distributing devices and is preferably provided with a priming or actuating tank which together with the distributing system itself may normally contain water or other non-freezing extinguishing liquid for low temperature work. Under emergency conditions additional extinguishing liquid may be supplied to the distributing system by any suitable liquid supply, such as an automatic chemical supply tank which may have its chemical mixing devices located within the tank itself if desired so as to supply the extinguishing liquid under high pressure through a supply connection between the tank and the distributing system which preferably has a check valve and may also be provided with an automatically closing venting drain device located between two check valves or the like. By providing a suitable connection between the upper part of the distributing system or actuating tank and the chemical supply tank or supply connection therefrom the suction or pressure reduction automatically caused under emergency conditions of the system may actuate the chemical mixing devices, and if desired additional supplies of extinguishing liquid may be furnished to the distributing system by a steamer connection or other non-automatic supplemental liquid supply communicating with the system through a suitable check valve or the like.

The accompanying drawing shows in a somewhat diagrammatic way illustrative embodiments of this invention in elevation, parts being shown in section to more clearly indicate their construction.

The distributing system may be of any desired type and may as indicated comprise one or more risers or supply pipes 1 to which

may be connected various distributing pipes 55 such as 2, on which automatic sprinkler heads or distributing devices 3 may be arranged at suitable intervals and the system may also comprise other distributing devices such as the hose connection 5 to which hose lines 60 may be connected and operated when the valve 4 is opened. A suitable actuating or priming supply tank may in many cases be connected to any suitable part of the distributing system when a wet pipe type of 65 distributing system is used so as to normally maintain the desired amount of extinguishing liquid in the system. The actuating tank is preferably in any case large enough to supply the liquid required to compensate 70 for any slight accidental leakage in the system and also in many cases may with advantage be of sufficient capacity to furnish an initial supply of extinguishing liquid when the system first gets into action in the event 75 of fire for which purpose it is sometimes desirable to have this supply tank initially under considerable air pressure where a more forcible discharge of the extinguishing liquid is desired. The desired head may, 80 however, be readily secured by the action of gravity when the upper part of the distributing system with or without the actuating or priming supply tank, such as 6, is carried up sufficiently beyond the distributing devices 85 and in such an arrangement as is diagrammatically illustrated in the drawing it is usually desirable to provide in connection with the top of the tank or adjacent parts of the distributing system a suitably reduced 90 venting device normally having a pin hole or reduced venting passage for the slow escape or ingress of air caused by ordinary temperature changes, and so forth. The venting passage 8 may be used in this connection and may be controlled by the venting valve 9 preferably of the needle valve type so as to be normally entirely shut or 95 preferably nearly closed to give the desired normal reduced venting passage and which 100 may be readily opened to allow the more free venting of air through the venting passage 8 when filling the actuating tank and other parts of the distributing system in the first place with the water or other aqueous 105 extinguishing liquid 7 such as a suitable solution of soluble and substantially inert salts to reduce the freezing point of the liquid

for low temperature work which should preferably be so selected as to be substantially inert or neutral to the other extinguishing liquids employed in connection 5 with the system.

Under emergency conditions when one or more of the automatic sprinkler heads open or when the other distributing devices are brought into play the extinguishing liquid 10 in the system is instantly available for putting out the fire and the discharge of this liquid involves the withdrawal of liquid from the substantially closed upper portion of the distributing system which may include 15 the actuating tank so as to cause a decided pressure reduction or suction therein. Any suitable emergency devices may be used in connection with the actuating tank or connected parts for automatically supplying 20 additional extinguishing liquid to the system or for alarm purposes or both, and these emergency devices may be located at any convenient point and may be connected with the actuating tank or connected parts in 25 which the pressure reduction takes place in any suitable way, as for instance, by the suitable actuating or suction connection or pipe 10 which is preferably connected to the distributing system above the normal liquid 30 level therein so that the air or other fluid in this suction connection more readily transmits the suction or pressure impulse.

Any supplemental fluid supply for the distributing system, such as any pressure 35 actuated automatic supplemental liquid supply may be used to supply additional extinguishing fluid under emergency conditions. A chemical pressure actuated arrangement is shown in the drawing as comprising 40 a chemical supply tank 16 which may be connected with the distributing system in any suitable way, this supply connection being preferably though not necessarily of an automatic venting character so as to 45 prevent or minimize mixture of the liquid in the distributing system and the liquid used in the chemical supply tank. The supply connection 11 may be used with advantage to connect the chemical or other pressure 50 operated supply tank with the co-operating distributing system and may comprise any suitable cut-off or check valve such as 13, between the distributing system and supply tank and may also if desired comprise 55 any suitable automatic venting drain device between the valve and tank. As indicated this venting device 31 may comprise the ball drip easing 35 in which the ball valve 14 may normally rest in a suitable seat or depression 60 between the stop pin 34 and the conical valve seat 15 so as to normally leave free the venting opening 36 for the escape of air or other material. Under emergency conditions, however, when fluid is dis- 65 charged in considerable quantities the ball

valve 14 is thereby carried against the seat 15 tightly closing this small drip opening which for clearness is shown considerably enlarged. It is usually desirable where such a venting or drain device is used in the supply connection between the distributing system and the point where the suction connection communicates with the supply connection or with the connected supply tank, to have one or more suitable cut-off valve devices 70 controlling the communication between the venting device and the connection with the tank and distributing system. The supply connection may have a depending portion, such as 18, extending within the supply tank, 75 so that its receiving end 19 is adjacent the bottom of the tank where if desired it may be provided with a suitable strainer, such as 19, of wire gauze or the like. If desired also a pin hole or reduced equalizing aperture 80 may be formed in the supply connection inside the tank and preferably adjacent the top of the air space therein so as to allow for the equalizing flow of any air or gases from time to time to compensate 85 for temperature changes without interfering with the emergency action of the apparatus. For this purpose the pipe 20 may communicate with the supply connection adjacent the top of the tank and be provided 90 with a diaphragm or the like 21 in which the pin hole or reduced equalizing aperture 22 may be formed, thus allowing a reduced opening between the air space of the supply tank and the supply connection. Any suitable chemical mixing devices may be used 100 in connection with the supply tank and the actuating members controlling these mixing devices are preferably located within the tank itself as generally indicated in the 105 Cooney Patents 1,075,015, 1,075,017 and 1,075,018 of October 7, 1913. These actuating members within the tank may comprise the actuating piston 23 mounted within the cylinder 17 communicating with or forming 110 part of the supplying connection so that the piston is drawn toward the end of this cylinder when suction occurs in the supply connection above and thus leave a substantially 115 free passage for the liquid up the extension 18 and into the supply connection 11 toward the distributing system. The suction connection or pipe 10 may be conveniently connected to the cylinder 17 or to the supply connection 11 at any convenient point so 120 that under emergency conditions the suction or pressure reduction caused by the withdrawal of liquid from the upper part of the distributing system at once causes a corresponding suction or pressure reduction on 125 the piston 23 within the cylinder 17 so as to cause its emergency operation and effect the actuation of the pressure generating elements. One or more check valves or cut-off devices such as 12 should for most effec- 130

tive operation be interposed in the supply connection between the distributing system and the point where the suction connection communicates with the supply connection so as to prevent any flow from the distributing system reducing its suction or actuating impulse. The supply tank may contain a charge 29 of suitable carbonate liquid and the mixing devices may comprise the tipping acid container 26 carrying the charge 27 of strong sulfuric acid or the like and mounted by its trunnions 28 in the support 30 so that it normally tends to overturn when the actuating stem 24 connected to the piston 23 is withdrawn from the socket or member 25 on the container.

It is also desirable to arrange for a further supply of extinguishing liquid to the distributing system and it is advantageous 20 to provide a suitable non-automatic supplemental liquid supply, such as a steamer connection preferably extending outside of the building so that steam fire engines may couple their hose lines thereto and pump 25 additional supplies of water into the distributing system in the event of fire. Such a steamer connection is shown as comprising the non-automatic supply connection and the two communicating hose connections 32 30 communicating with the distributing system through the automatic check or cut-off valve 33 which prevents loss of extinguishing liquid in the system through this connection while instantly allowing any additional 35 supplies of liquid to be pumped therethrough into the distributing system.

This invention has been described in connection with a number of illustrative embodiments, forms, elements, materials, parts and 40 arrangements, to the details of which disclosure the invention is not of course to be limited, since what is claimed as new and what is desired to be secured by Letters Patent is set forth in the appended claims 45 which are of a somewhat limited character in view of the fact that broader claims to the use of an actuating tank or other substantially closed upper portion of a distributing system and the connected suction 50 or actuating connection therewith are made in other applications such as Serial Nos. 799,840, filed November 8, 1913, 814,032 and 814,033, filed January 24, 1914.

What is claimed is:

55 1. In automatic fire extinguishing apparatus, a distributing system normally charged with non-freezing extinguishing liquid and comprising automatic distributing devices including automatic sprinkler heads and hose connections, an actuating supply tank containing a charge of said extinguishing liquid and connected to the upper part of said distributing system, a reduced area venting device connected to the 60 upper part of said distributing system, the

upper part of said distributing system being substantially closed under emergency conditions to permit a pressure change to take place therein on the emergency operation of the system, an automatic supplemental fluid supply for said distributing system comprising a chemical supply tank, a supply connection between said chemical supply tank and said distributing system to supply additional extinguishing liquid thereto, 75 chemical mixing devices co-operating with said supply tank and comprising a tipping acid container and actuating members comprising an actuating piston arranged in a cylinder formed in said supply connection and 80 located within said tank, a suction connection between the air space in the upper part of said distributing system and said supply connection adjacent said chemical supply tank and a check valve cut-off device in said 85 supply connection between said suction connection and said distributing system.

2. In automatic fire extinguishing apparatus, a distributing system normally charged with non-freezing extinguishing 90 liquid and comprising automatic distributing devices including automatic sprinkler heads, an actuating supply tank containing a charge of said extinguishing liquid and connected to the upper part of said distributing system, the upper part of said distributing system being substantially closed under emergency conditions to permit a pressure change to take place therein on the emergency operation of the system, 95 an automatic supplemental fluid supply for said distributing system comprising a chemical supply tank, a supply connection between said chemical supply tank and said distributing system to supply additional extinguishing liquid thereto, chemical mixing devices co-operating with said supply tank and comprising a tipping acid container and actuating members comprising an actuating piston arranged in a cylinder formed in said supply connection and located within said tank, a suction connection between the air space in the upper part of said distributing system and said supply connection adjacent said chemical supply tank, and a 100 check valve cut-off device in said supply connection between said suction connection and said distributing system.

3. In automatic fire extinguishing apparatus, a distributing system normally charged with non-freezing extinguishing 120 liquid and comprising automatic distributing devices including automatic sprinkler heads, the upper part of said distributing system being substantially closed under emergency conditions to permit a pressure change to take place therein on the emergency operation of the system, an automatic supplemental fluid supply for said distributing system comprising a chemical supply 125

130

off device in said supply connection between said suction connection and said distributing system.

9. In automatic sprinkler fire extinguishing apparatus, a distributing system normally charged with extinguishing liquid and comprising automatic distributing devices including automatic sprinkler heads and hose connections, an actuating supply tank containing a charge of said extinguishing liquid and connected to the upper part of said distributing system, a reduced area venting device connected to the upper part of said actuating tank, the upper part of 5 said distributing system extending above the operating distributing device and being substantially closed under emergency conditions to permit a pressure change to take place therein on the emergency operation of the system, an automatic supplemental fluid supply for said distributing system, a supply connection between said supplemental fluid supply and said distributing system to supply additional extinguishing liquid thereto, a suction connection controlling said automatic supplemental fluid supply and communicating with the air space in the upper part of said distributing system, a check valve cut-off device in said supply 10 connection between said suction connection and said distributing system, an automatically closing venting drain device in said supply connection between said cut-off device and said suction connection and a second automatic check valve cut-off device in said supply connection between said venting device and said suction connection.

10. In automatic fire extinguishing apparatus, a distributing system normally charged with extinguishing liquid and comprising automatic distributing devices, a reduced area venting device connected to the upper part of said distributing system, the upper part of said distributing system extending above the operating distributing device and being substantially closed under emergency conditions to permit a pressure change to take place therein on the emergency operation of the system, an automatic supplemental fluid supply for said distributing system, a supply connection between said supplemental fluid supply and said distributing system to supply additional extinguishing liquid thereto, a suction connection 40 controlling said automatic supplemental fluid supply and communicating with the air space in the upper part of said distributing system, an automatic check valve cut-off device in said supply connection between said suction connection and said distributing system and said venting device and a second automatic check valve cut-off device in said supply connection between said venting device and said suction connection.

11. In automatic fire extinguishing apparatus, a distributing system normally charged with extinguishing liquid and comprising automatic distributing devices, the upper part of said distributing system extending above the operating distributing device and being substantially closed under emergency conditions to permit a pressure change to take place therein on the emergency operation of the system, an automatic supplemental fluid supply for said distributing system, a supply connection between said supplemental fluid supply and said distributing system to supply additional extinguishing liquid thereto, a suction connection controlling said automatic supplemental fluid supply and communicating with the upper part of said distributing system and said automatic fluid supply, an automatic check valve cut-off device in said supply connection between said suction connection and said distributing system, a venting drain device in said supply connection between said cut-off device and said suction connection and a second automatic check valve cut-off device in said supply connection between said venting device and said suction connection.

12. In automatic fire extinguishing apparatus, a distributing system normally charged with extinguishing liquid and comprising automatic distributing devices, the upper part of said distributing system extending above the operating distributing device and being substantially closed under emergency conditions to permit a pressure change to take place therein on the emergency operation of the system, an automatic supplemental fluid supply for said distributing system, a supply connection between said supplemental fluid supply and said distributing system to supply additional extinguishing liquid thereto, actuating members communicating with said supply connection, a suction connection between the air space in the upper part of said distributing system and said actuating members, an automatic cut-off device in said supply connection between said suction connection and said distributing system, a venting drain device in said supply connection between said cut-off device and said suction connection and a second automatic cut-off device in said supply connection between said venting device and said suction connection.

13. In automatic fire extinguishing apparatus, a distributing system normally charged with extinguishing liquid and comprising automatic distributing devices, the upper part of said distributing system extending above the operating distributing device and being substantially closed under emergency conditions to permit a pressure change to take place therein on the emergency operation of the system, an automatic supplemental fluid supply for said distributing system, a supply connection between said supplemental fluid supply and said distributing system to supply additional extinguishing liquid thereto, actuating members communicating with said supply connection, a suction connection between the air space in the upper part of said distributing system and said actuating members, an automatic cut-off device in said supply connection between said suction connection and said distributing system, a venting drain device in said supply connection between said cut-off device and said suction connection and a second automatic cut-off device in said supply connection between said venting device and said suction connection.

- charge to take place therein on the emergency operation of the system, an automatic supplemental fluid supply for said distributing system, a supply connection between 5 said supplemental fluid supply and said distributing system to supply additional extinguishing liquid thereto, actuating members communicating with said supply connection, a suction connection between the 10 upper part of said distributing system and said actuating members and an automatic cut-off device in said supply connection between said suction connection and said distributing system.
14. In fire extinguishing apparatus, a distributing system comprising an upper suction portion substantially closed under emergency conditions and distributing devices including automatic sprinkler heads below 20 said suction portion, non-freezing extinguishing liquid in said distributing system, an automatic supplemental fluid supply comprising a chemical supply tank communicating with said system and including actuating members located in said tank, a suction connection communicating with the upper suction portion of said distributing system and automatically operating said actuating members under emergency conditions to 30 supply additional extinguishing fluid to said system and automatic cut-off and venting devices between said supplemental fluid supply and said system.
15. In fire extinguishing apparatus, a distributing system comprising an upper suction portion substantially closed under emergency conditions and distributing devices below said suction portion, non-freezing extinguishing liquid in said distributing system, an automatic supplemental fluid supply comprising a chemical supply tank communicating with said system and including actuating members located in said tank and a suction connection communicating with 40 the upper suction portion of said distributing system and automatically operating said actuating members under emergency conditions to supply additional extinguishing fluid to said system.
16. In fire extinguishing apparatus, a distributing system comprising a suction portion in which a pressure reduction is produced under emergency conditions and distributing devices below said suction portion, non-freezing extinguishing liquid in said distributing system, an automatic supplemental fluid supply comprising a chemical supply tank communicating with said system and including actuating members located in said tank and a suction connection 50 communicating with the suction portion of said distributing system and automatically operating said actuating members under emergency conditions to supply additional extinguishing fluid to said system.
17. In automatic fire extinguishing apparatus, a distributing system normally charged with non-freezing extinguishing liquid and comprising automatic distributing devices including automatic sprinkler heads, a reduced area venting device connected to the upper part of said system, the upper part of said distributing system being substantially closed under emergency conditions to permit a pressure change to 70 take place therein on the emergency operation of the system, an automatic supplemental fluid supply for said distributing system comprising a chemical supply tank, a supply connection between said chemical supply tank and said distributing system to supply additional extinguishing liquid thereto, chemical mixing devices co-operating with said supply tank and connected with said supply connection, a fluid actuating connection to actuate said supplemental fluid supply and extending between the air space in the upper part of said distributing system and said supply connection adjacent said chemical supply tank, an automatically 80 closing venting drain device in said supply connection between said distributing system and said suction connection and cut-off devices automatically opening toward said distributing system arranged in said supply connection and normally closed on both sides of said drain device.
18. In automatic fire extinguishing apparatus, a distributing system normally charged with extinguishing liquid and comprising automatic distributing devices, the upper part of said distributing system being substantially closed under emergency conditions to permit a pressure change to take place 90 therein on the emergency operation of the system, an automatic supplemental fluid supply for said distributing system comprising a chemical supply tank, a supply connection between said chemical supply tank and said distributing system to supply additional extinguishing liquid thereto, chemical mixing devices co-operating with said supply tank and connected with said supply connection, a fluid actuating connection to 100 actuate said supplemental fluid supply and extending between the upper part of said distributing system and said supply connection, an automatically closing venting drain device in said supply connection between said distributing system and said suction connection and cut-off devices automatically 110 opening toward said distributing system arranged in said supply connection and normally closed on both sides of said drain device.
19. In automatic fire extinguishing apparatus, a distributing system normally charged with extinguishing liquid and comprising distributing devices, the upper part of said distributing system being substantially closed 120

under emergency conditions to permit a pressure change to take place therein on the emergency operation of the system, an automatic supplemental fluid supply for said

5 distributing system comprising a supply tank, a supply connection between said supply tank and said distributing system to supply additional extinguishing liquid thereto, a fluid actuating connection to actuate said

10 supplemental fluid supply and extending from the upper part of said distributing system, an automatically closing venting drain device in said supply connection between said distributing system and said sup-

15 a drain distributing system and said suction connection and cut-off devices automatically opening toward said distributing system arranged in said supply connection and normally closed on both sides of said drain device.

20 20. In automatic fire extinguishing appa-

ratus, a distributing system comprising distributing devices, the upper part of said distributing system being substantially closed under emergency conditions to permit a pressure change to take place therein on the

emergency operation of the system, an automatic supplemental fluid supply for said distributing system comprising a supply tank, a supply connection between said supply tank and said distributing system, to

35 and said distributing system to supply additional extinguishing liquid there-
to, a fluid actuating connection to actuate said supplemental fluid supply and extending from the upper part of said distributing

33 system, a venting drain device in said supply connection between said distributing system and said suction connection and cut-off devices automatically opening toward said distributing system arranged in said supply

40 connection and normally
sides of said drain device

21. In automatic fire extinguishing apparatus, a distributing system comprising distributing devices, the upper part of said distributing system being substantially closed under emergency conditions to prevent

under emergency conditions to permit a pressure change to take place therein on the emergency operation of the system, an automatic supplemental fluid supply for said distributing system, a supply connection between said supplemental fluid supply and

55 between said supplemental fluid supply and said distributing system to supply additional extinguishing liquid thereto, a fluid actuating connection to actuate said supplemental fluid supply and extending from the upper

part of said distributing system, a venting drain device in said supply connection between said distributing system and said suction connection and cut-off devices automatically opening toward said distributing sys-

system arranged in said supply connection and normally closed on both sides of said drain device.

22. In automatic fire extinguishing apparatus, a distributing system comprising

distributing devices, the upper part of said distributing system being substantially closed under emergency conditions to permit a pressure change to take place therein on the emergency operation of the system, 70 an automatic supplemental fluid supply for said distributing system, a supply connection between said supplemental fluid supply and said distributing system to supply additional extinguishing liquid thereto, a fluid actuating connection to actuate said supplemental fluid supply and extending from the upper part of said distributing system, a venting drain device in said supply connection between said distributing system and said suction connection and check valves automatically opening toward said distributing system arranged in said supply connection and normally closed on both sides of said drain device. 80 85 90 95

23. In fire extinguishing apparatus, a distributing system comprising distributing devices, non-freezing extinguishing liquid in said system, an automatic fluid supply comprising a chemical supply tank, a supply connection between said supply and said system to supply additional extinguishing liquid thereto under emergency conditions, a suction connection between the upper portion of said distributing system and said supply connection and mechanism controlled thereby to automatically operate said fluid supply, a normally open drain device in said supply connection between said distributing system and said suction connection and normally closed check-valves in said supply connection on both sides of said drain device and automatically opening toward said distributing system under emergency conditions.

24. In fire extinguishing apparatus, a distributing system comprising distributing devices, extinguishing liquid in said system, an automatic fluid supply comprising a chemical supply tank, a supply connection between said supply and said system to supply additional extinguishing liquid thereto under emergency conditions, a suction actuating connection communicating with the upper part of said distributing system and with said supply connection to automatically operate said fluid supply, a normally open drain device in said supply connection between said distributing system and said suction connection, means to close said drain device under emergency conditions and normally closed cut-off devices in said supply connection on both sides of said drain device and automatically opening toward said distributing system under emergency conditions. 105 110 115 120 125

25. In fire extinguishing apparatus, a distributing system comprising distributing devices, extinguishing liquid in said system, an automatic fluid supply comprising a 130

chemical supply tank, a supply connection between said supply and said system to supply additional extinguishing liquid thereto under emergency conditions, a suction actuating connection communicating with the upper part of said distributing system and with said supply connection to automatically operate said fluid supply, a normally open drain device in said supply connection between said distributing system and said suction connection and normally closed cut-off devices in said supply connection on both sides of said drain device and automatically opening toward said distributing system under emergency conditions.

26. In fire extinguishing apparatus, a distributing system comprising automatic distributing devices, non-freezing extinguishing liquid in said distributing system, an automatic fluid supply comprising a chemical supply tank connected to said distributing system, means to automatically operate said fluid supply under emergency conditions, a supply connection between said supply tank and said distributing system to supply additional extinguishing liquid thereto, a normally open venting drain device in

said supply connection, means for automatically closing said drain device under emergency conditions and a normally closed cut-off device in said supply connection between said drain device in said distributing system and automatically opening toward said distributing system.

27. In fire extinguishing apparatus, a distributing system comprising distributing devices, extinguishing liquid in said distributing system, an automatic fluid supply comprising a chemical supply tank, means to automatically operate said supply under emergency conditions, a supply connection between said supply tank and said distributing system to supply additional extinguishing liquid thereto, a normally open drain device in said supply connection and a normally closed cut-off device in said supply connection between said drain device in said distributing system and automatically opening toward said distributing system.

Corrections in Letters Patent No. 1,287,800.

It is hereby certified that in Letters Patent No. 1,287,800, granted December 17, 1918, upon the application of Everett L. Thompson, of Dover, New Jersey, for an improvement in "Automatic Fire-Extinguishing Apparatus," errors appear in the printed specification requiring correction as follows: Page 5, lines 85-86, claim 11, strike out the words "and said automatic fluid supply"; page 6, line 1, claim 13, for the word "charge" read *change*; and that the said Letters Patent should be read with these corrections therein that the same may conform to the record of the case in the Patent Office.

Signed and sealed this 25th day of February, A. D., 1919.

[SEAL.]

F. W. H. CLAY,

Acting Commissioner of Patents.
